(57) **CLAIM**

We claim the ornamental design for a lock, as shown and described.

DESCRIPTION

FIG. 1 is a perspective view of a lock showing our new design;

FIG. 2 is a top view of the lock of FIG. 1;

FIG. 3 is a front view of the lock of FIG. 1;

FIG. 4 is a rear view of the lock of FIG. 1;

FIG. 5 is a bottom view of the lock of FIG. 1;

FIG. 6 is a right side view of the lock of FIG. 1; and,

FIG. 7 is a left side view of the lock of FIG. 1.

The portions of the Figures shown in broken lines are not part of the claimed design and are for illustration only.
